V. NICOSIA.

HAIR CLIPPER.

APPLICATION FILED MAR. 29, 1919.

1,351,924.

Patented Sept. 7, 1920.

INVENTOR,
Vincent Nicosia
BY John M. Spellman
ATTORNEY.

UNITED STATES PATENT OFFICE.

VINCENT NICOSIA, OF WACO, TEXAS.

HAIR-CLIPPER.

1,351,924.

Specification of Letters Patent.

Patented Sept. 7, 1920.

Application filed March 29, 1919. Serial No. 286,121.

To all whom it may concern:

Be it known that I, VINCENT NICOSIA, a citizen of the United States, residing at Waco, in the county of McLennan and State of Texas, have invented certain new and useful Improvements in Hair-Clippers, of which the following is a specification.

My invention relates to improvements in hair clippers and in such connection it relates more particularly to a protector or attachment for hair clippers.

The ordinary hair clipper has a flat bottom plate with teeth or knives with reciprocating upper teeth, the clipper being held against the head or neck to keep the teeth in proper alinement with the hair, and this plate while ordinarily effective in a hair clipper, quite frequently causes the clippers to "dig" into the hair or abrade the person's skin.

The principal object of my invention is to provide a device of the character described which will allow the clippers to ride smoothly over the hair or skin and thus obviate the above mentioned difficulty.

Another object of my invention is to provide an attachment of the character described which is very simple, effective, and cheaply manufactured.

I provide a metal plate arranged to slip on the clippers, leaving the teeth of the clippers exposed say one quarter of an inch or more. The plate has a plurality of small rollers differing in diameter in order to provide a slant, so that the clippers maintain a correct angle to the hair and ride easily over same during the cutting operation.

My invention will be more fully understood from the following description, taken in connection with the accompanying drawings forming part hereof in which—

Figure 1 is a top or plan view of my invention, partly sectioned.

Fig. 2 is an end elevational view looking toward the curved portion of the device.

Fig. 3 is a cross sectional view taken on line 3—3 of Fig. 1, and

Fig. 4 is a bottom view of a pair of

clippers embodying my invention, the handles partly broken away.

Referring to the drawings, 1 represents a pair of hair clippers embodying my invention, the handles of the clippers partly broken away, showing my protector 2 attached to the bottom plate 3 of the clippers. The protector 2 is constructed of some light metal and has its inner end 4 semicircular and the sides 5—5 bent upward and slightly inward as shown at Fig. 2, so that when the attachment is slipped on over the bottom plate 3 of the clippers there is sufficient resiliency in the sides 5—5 to hold the device firmly in place.

The protector has channels or slits 6—6 (see Fig. 3) extending across the bottom thereof wherein is placed small wires 7, the wires being threaded through small tubular rollers 8 and 9 and fastened to the outside of the sides 5—5 by solder or otherwise. The roller 9 next the teeth of the clippers is slightly smaller than roller 8 in order that an angle of inclination may be provided to allow of proper alinement to the hair. While I have shown only two rollers, any desired number may be used, each of different diameter to allow of sufficient slant to the clippers.

Having thus described the nature and objects of my invention, what I claim as new and desire to secure by Letters Patent, is—

In a device of the character described, in combination with a hair clipper, of a detachable metal plate having a plurality of small tubular rollers of different diameters set in slits in and extending across the surface of the plate, the roller or rollers next the handles of said clipper being larger than those following in the ratio to provide a good cutting angle to the hair, the sides of said plate having suitable flanges to attach the device to the clippers.

In testimony whereof I have signed my name to this specification.

VINCENT NICOSIA.
